FIG. 2.

INVENTOR:
GORDON R. ANDERSON

BY *Paul L. Kohler*
ATTORNEY

UNITED STATES PATENT OFFICE

141,137

DESIGN FOR A DYNAMOELECTRIC MACHINE

Gordon R. Anderson, Beloit, Wis., assignor to
Fairbanks, Morse & Co., Chicago, Ill., a corpo-
ration of Illinois

Application February 28, 1944, Serial No. 112,733

Term of patent 14 years

(Cl. D26—5)

To all whom it may concern:

Be it known that I, Gordon R. Anderson, a citizen of the United States, residing at Beloit, in the county of Rock and State of Wisconsin, have invented a new, original, and ornamental Design for Dynamoelectric Machine, of which the following is a specification, reference being had to the accompanying drawing, forming part thereof.

In the drawing

Fig. 1 is a top plan view of a dynamoelectric machine showing my new design;

Fig. 2 is a bottom plan view thereof;
Fig. 3 is a view in side elevation, of the dynamoelectric machine, and

Fig. 4 is an opposite side elevational view of the dynamoelectric machine.

I claim:

The ornamental design for a dynamoelectric machine, as shown.

GORDON R. ANDERSON.
